UNITED STATES PATENT OFFICE.

JOHN YOUNG, OF TOLEDO, OHIO.

ELECTRIC TROLLEY.

No. 896,189.

Specification of Letters Patent. Patented Aug. 18, 1908.

Application filed April 29, 1908. Serial No. 429,921.

To all whom it may concern:

Be it known that I, JOHN YOUNG, a citizen of the United States, residing at Toledo, in the county of Lucas and State of Ohio, have 5 invented certain new and useful Improvements in Electric Trolleys; and I do hereby declare the following to be a full, clear, and exact description of the invention, such as will enable others skilled in the art to which 10 it appertains to make and use the same.

This invention relates to rolling trolley contacts for use on electrically propelled vehicles, and a particular object of the invention is to provide a device of this character 15 in which friction and wear are reduced to a minimum.

The invention embodies certain novel features of construction and the arrangement of the parts hereinafter shown, described and 20 claimed.

In the accompanying drawings, Figure 1 is a side elevation of a rolling trolley contact constructed in accordance with my invention; Fig. 2 is a like view with half of the 25 inclosing case for the contact ring removed; Fig. 3 is a vertical section on line $x-x$, Fig. 2.

Referring to the details, 1 is a forked harp fixed at the free end of a trolley pole and between the arms of the harp is eccentrically 30 mounted so as to swing freely by gravity, a case 2 constructed of like half sections secured together at the margin by screws 3 or other suitable fastening means. The general form of the case is a hollow disk, open at 35 the top, at 4, and near the top margin between the side walls of the case are mounted rollers 5 and 6 rotatable upon pins 7 and 8 the ends of which are supported in the case.

9 is a grooved contact ring adapted to roll 40 along the trolley conductor 10, the same being preferably constructed of brass with an inner face 11 of a harder metal, such as steel or chilled cast iron, and adapted to roll in contact with the faces of the rollers 5 and 6.

45 Suitably supported within the case be-

tween its sides to underlie and partially surround the rollers 5 and 6 is a basket or lubricating chamber 12 adapted to hold waste or other suitable absorbent material saturated with oil, or, powdered graphite and oil may 50 be placed in the chamber 12 to lubricate the rollers and their bearing surfaces. As shown in Fig. 2, the chamber 12 is held in place between the sides of the case by suitable projecting lugs on the inner walls of the case, 55 although other means may be employed to support a lubricating chamber adjacent to the rollers. To assist in suspending the case in a true vertical direction from the forked harp, the lower portion 14 of the case is 60 made excessively heavy by increasing the thickness of the metal walls. It is thus observed that when the device is in operation, the annular contact ring will bear upon the two rollers mounted in the case, and with the 65 provision for lubricating the rollers the friction and wear between the faces in rolling contact will be reduced to a minimum.

Having described my invention, what I claim and desire to secure by Letters Patent, 70 is:

1. In an electric trolley, the combination with a forked harp, of an eccentrically mounted case suspended from the harp, rollers mounted in the case, and an annular contact 75 ring rotatable upon the rollers.

2. In an electric trolley, the combination with a forked harp, of an eccentrically mounted case suspended from the harp and having a preponderance of weight at its lower end, 80 rollers mounted in the case, a chamber containing lubricant supported by the case adjacent to the rollers, and an annular contact ring rotatable upon the rollers.

In testimony whereof, I hereunto affix my 85 signature, in presence of two witnesses.

JOHN YOUNG.

Witnesses:

CARL H. KELLER,
GRANT WILLIAMS.
